ATTORNEY.

UNITED STATES PATENT OFFICE.

PENELOPE FYNN, OF DENVER, COLORADO.

DESIGN FOR A DOLL.

59,210.

Specification for Design. Patented Oct. 4, 1921.

Application filed March 22, 1921. Serial No. 454,491. Term of patent 7 years.

To all whom it may concern:

Be it known that I, PENELOPE FYNN, a citizen of the United States, residing at Denver, in the county of Denver and State of Colorado, have invented a new, original, and ornamental Design for Dolls, of which the following is a specification, reference being had to the accompanying drawing, forming part thereof.

Fig. 2, a side view of the same.

I claim:

The ornamental design for a doll, as shown.

In testimony whereof I have affixed my signature.

PENELOPE FYNN.
